MANUFACTURE OF WIRE FABRICS

Otto Carl Scherfel, Philadelphia, Pa., assignor to
Audubon Wire Cloth Corporation, Philadelphia,
Pa., a corporation of New Jersey

Application May 15, 1940, Serial No. 335,411

14 Claims. (Cl. 245—6)

My invention relates to wire fabric made of helically coiled wires disposed in parallel relation and maintained in interrelated arrangement transversely thereof.

The improvements constituting the subject of my present invention relate more particularly to the longitudinal reinforcement of wire fabrics of the type in which the helically coiled wires are connected by cross connector rods. Wire fabric of this type is usually made of helically coiled wires of different twist which alternate throughout the entire extent of the fabric—right-hand or dextrorsal wires alternating with left-hand or sinistrorsal wires—and all of said wires being maintained in their connected relation by means of cross rod connectors engaging alternately the bights of the coils of pairs of directly adjacent wires of different twist and said cross connector rods being permanently secured to the ends of the respective helically coiled wires. By having wires of different twist in alternating relation, the helices or coils of the same lie at different angles, transversely and longitudinally, upon what may be termed the surfaces of the fabric and when such fabric is employed as a carrying or conveying element, such disposition of the coils or helices of the wires of different twist eliminates any tendency of such carrying element or conveyer to shift from one side to the other and insures that it will track true when passing over the pulleys and idlers of the mechanism employed for imparting movement to the same.

The cross rod connectors for the helically coiled wires are of an undulatory or crimped type, and the bends of such rods are so spaced as to be in position for engagement by the oppositely disposed bights of the helices or coils of the respective helically coiled wires. The ends of the helically coiled wires are positively connected with the ends of the crimped cross connector rods; each cross rod being connected to the ends of a single helically coiled wire, and by preference these connections are in the form of welds. The respective helically coiled wires of different twist have helices of material length widthwise thereof and they are relatively flat. My improved fabric is of extreme strength and flexibility; has no appreciable stretch longitudinally and will not contract transversely.

One object of my invention is to reinforce, strengthen and, to a certain extent, stiffen the individual helically coiled wires employed in the construction of my improved fabric.

A further object of my invention is to rein-

force, strengthen and, to a certain extent, stiffen the marginal edges or selvages and other portions or areas of the wire fabric.

A further object of my invention is to provide the body portion of the wire fabric with strengthening and reinforcing portions or areas.

A further object of my invention is to permanently secure the ends of each of the cross connector rods upon which the helically coiled wires are hinged to one of said latter wires so that in its completed form the fabric is composed of unit elements; each consisting of a helically coiled wire and a cross connector wire.

And a still further object of my invention is to provide a wire fabric with marginal edges or selvages highly resistant to wear.

These and other features of my invention are more fully set forth hereinafter; reference being had to the accompanying drawing, more or less diagrammatic in character, in which:

Fig. 1 is a plan view, partly broken away, of one form of wire fabric having features forming the subject of my present invention.

Figs. 2 and 3 are enlarged views of portions of the fabric shown in Fig. 1, illustrating in greater detail features of my present invention.

Fig. 4 is an elevation of one of the marginal edges of the fabric shown in Fig. 1.

Fig. 5 is a plan view, partly broken away, illustrating another form of wire fabric embodying features within the scope of my present invention.

Fig. 6 is an enlarged view of a portion of the fabric shown in Fig. 5, illustrating in greater detail the reinforcing feature of the same, and

Fig. 7 is an elevation of one of the marginal edges of the fabric shown in Fig. 5.

In the form of my improved fabric illustrated in Figs. 1, 2 and 3 of the drawing, the helically coiled wires are of different twist and are indicated at 10 and 11; the said wires being of right-hand or dextrorsal twist and left-hand or sinistrorsal twist, respectively.

These helically coiled wires when of different twist are arranged alternately throughout the entire extent of the fabric and in order that the respective sets of wires may be connected into a complete fabric, cross connector rods 12 and 13 are employed; such cross rod connectors being crimped and the several bends produced by the crimping are so spaced as to be engaged by the bights of the coils or helices of the respective wires. The ends of the helically coiled wires 10 are connected to the ends of the crimped cross connector rods 12, by welding, as indicated at x,

and the ends of the helically coiled wires 11 are also connected to the ends of the crimped cross connector rods 13, by welding, as indicated at y. These welded connections are at the extreme margins of the belt and are of material value in resisting wear at the edges thereof. In a sense, the fabric may be described as composed of a series of units; units consisting of a helically coiled wire 10 and a cross connector rod 12, alternating with units consisting of a helically coiled wire 11 and a cross connector rod 13. In the form of my improved fabric illustrated in Figs. 5 and 6 of the drawing, the helically coiled wires are also of different twist and are indicated at 110 and 111; the said wires being of right-hand twist and left-hand twist, respectively.

As in the structure illustrated in Fig. 1, these wires of different twist are arranged alternately and are connected into a complete fabric by cross rods 112 and 113, which are crimped and have their bends so spaced as to be engaged by the bights of the coils or helices of the respective wires 110 and 111. The ends of the wires 110 are connected to the ends of the crimped cross rods 112, by welding, as indicated at x', and the ends of the wires 111 are also connected to the ends of the crimped cross rods 113, by welding, as indicated at y'. These welded connections are at the extreme margins of the belt and are of material value in resisting wear at the edges thereof. This fabric, like the form shown in Fig. 1, may be described as composed of a series of units; units consisting of a helically coiled wire 110 and a cross rod 112, alternating with units consisting of a helically coiled wire 111 and a cross rod 113.

For the purpose of relatively stiffening the respective wires of the fabric and providing strengthening and reinforcing means for different areas of the same, including the selvages as well as the body portion thereof in wire fabric of the character illustrated in Fig. 1 of the drawing, certain of the coils or helices of the helically coiled wires are compressed or condensed so as to lie substantially or directly in engagement with each other and in such relation that at certain portions of the fabric two or more coils or helices of each helically coiled wire are in engagement with single bends of the crimped cross connector rods.

In the structure illustrated in Fig. 1, each of the helically coiled cross wires is provided with a plurality of these closely engaging coils or helices. Considering one of the helically coiled wires 10, for instance, it will be observed that it is provided at each end with a pair of coils or helices in close relation; the closely placed coils at the left-hand side of the view being indicated at 10^a while the closely placed coils at the right-hand side thereof are indicated at 10^b. The coils 10^a are at the marginal edge of the fabric while the coils 10^b are inwardly of the marginal edge. This is the showing on the face of the fabric as illustrated in Fig. 1. The closely placed coils 10^a and 10^b of the wire 10 are of right-hand twist, conforming to the twist of balance of the wire, but in developing this reinforcement, whether at the marginal edges or at another area of the fabric, it is necessary to provide helices or coils extending in the opposite direction, usually singly, and these are indicated at 10^c at the left-hand side of the figure and at 10^d at the right-hand side of the figure; the coil 10^c being inwardly of the marginal edge of the fabric.

fabric, while the coil 10^d at the right-hand side of the figure is directly at the marginal edge of the fabric. Each of the helically coiled wires of right-hand twist, indicated at 10, will have this arrangement at the marginal edges or selvages of the fabric. As the dotted line indications show, the coils or helices of the wire 10 are in a different relation at the under side of the fabric, as viewed in Fig. 1.

Upon considering one of the helically coiled wires 11, for instance, it will be observed that it is also provided at each end with a pair of coils or helices in close relation; the closely placed coils at the left-hand side of the view being indicated at 11^a while the coils at the right-hand side are indicated at 11^b. The coils 11^a are inwardly of the marginal edge while the coils 11^b are directly at the marginal edge. This is the showing on the face of the fabric as illustrated in Fig. 1. The closely placed coils 11^a and 11^b of the wire 11 are of left hand twist, conforming to the twist of the balance of the wire, but in developing this reinforcement, whether at the marginal edges or at another area of the fabric, it is necessary to provide helices or coils extending in the opposite direction, usually singly, and these are indicated at 11^c at the left-hand side of the figure and at 11^d at the right-hand side of the figure; the coil 11^c being at the marginal edge of the fabric, while the coil 11^d at the right-hand side of the figure is inwardly of the margin. Each of the helically coiled wires of left-hand twist, indicated at 11, will have this arrangement at the marginal edges of the fabric. As the dotted line indications show, the coils or helices of the wires 11 are in a different relation at the under side of the fabric as viewed in Fig. 1.

The result of the arrangement above described is the presence of two closely engaging coils or helices at or adjacent to the end of each helically coiled wire, and the effect of this arrangement is to relatively stiffen the respective wires and reinforce and strengthen the selvages of the fabric.

Within the body of the fabric, centrally thereof or at any other suitable point, I may arrange the special disposition of the helically coiled wires with close spacing of certain coils or helices, and it will be observed that this arrangement is exactly the same as the arrangement of closely engaging coils or helices at the ends of the respective wires 10 and 11; the pairs of closely placed coils being indicated at 10^e and 11^e respectively, and the single reversely placed coils of the respective wires 10 and 11 being indicated at 10^f and 11^f.

Thus, it will be observed, the bends at each end of the crimped cross connector rods 12 and 13 are engaged by the bights of three of the coils or helices of the wires 10 and 11 while the bends directly flanking the same are engaged by the bights of two of the helices or coils. The connections or engagement of the coils of the respective wires 10 and 11 in the body of the fabric are made in an exactly similar manner. This arrangement of the closely engaging coils in the body of the fabric produces what may be termed a strengthening rib or reinforcement longitudinally of the fabric of the same character as the strengthening and reinforcing means at the selvages of the fabric.

While I have indicated a single reinforcing or strengthening arrangement of the helices or coils in the body of the fabric, in Fig. 1, it will be un-

derstood that the helically coiled cross wires may be so arranged at a number of points in the body of the fabric if it be desired to further strengthen and reinforce the same; a condition that is usually determined by the width of the fabric. By reason of the welded connections of the ends of the cross connector rods with the ends of the helically coiled wires, the belt may be said to be composed of a series of units.

In the form of fabric illustrated in Figs. 5 and 6, the same arrangements of helically coiled wires of different twist, in alternating relation, is employed, connected by means of cross connector rods of crimped formation; the wires of right-hand twist alternating with wires of left-hand twist throughout the extent of the fabric. In this arrangement the strengthening and reinforcement of the marginal edges of the fabric is effected by arranging a number of the coils or helices at each end of the helically coiled wires in close engagement. In this form of my improved fabric, the wires of right-hand twist are indicated at 110 and the wires of left-hand twist are indicated at 111, and such wires are interrelated or connected by the crimped cross rods 112 and 113. Each end of each of the helically coiled wires 110 and 111 is provided with a series of coils or helices in close disposition, as clearly indicated at 110^a and 111^a.

In carrying out this arrangement of my improved fabric, it is desirable to omit the crimps at the end portions of the cross connector rods which are engaged by the closely placed helices or coils 110^a and 111^a; such rods having straight ends as indicated at 112^a and 113^a. The number of coils in this close formation may comprise four or five; five being illustrated in the present instance. The ends of the cross rods 112 and 113 are secured to the ends of the helically coiled wires 110 and 111, respectively, by welding the same thereto, as indicated at x' and y'. This connection is such that it provides a series of units, each consisting of a helically coiled wire and a cross rod, making up the fabric, as in the construction illustrated in Fig. 1.

While I have illustrated in Fig. 1 the use of helically coiled wires of different twist in alternate relation, it is within the scope of my invention to make a fabric in which all of the wires are of the same twist and are held together by crimped cross connector rods. It is also within the scope of my invention to employ a greater number of the closely placed coils or helices than the sets of pairs illustrated, and it is also within the scope of my invention to employ helically coiled wires in which all of the coils are in paired relation longitudinally of the same; thereby producing a highly reinforced fabric structure.

It will be understood that modifications may be made in the construction and arrangement of the several elements of my improved wire fabric structure without departing from the spirit of my invention, all of which is deemed to be within the scope of the appended claims.

I claim:

1. A wire fabric composed of a plurality of helically coiled wires, cross rods extending the full width of the fabric and connecting the bights of pairs of the several helically coiled wires; said cross rods being crimped with the bends so spaced as to be engaged by the helices or coils of the respective cross wires, and reinforcing and strengthening means for the selvages of said fabric comprising a plurality of closely placed

coils of the respective helically coiled wires disposed adjacent to the marginal edges of the fabric; each of said helically coiled wires being welded to an individual cross rod beyond said closely placed coils.

5 2. A wire fabric comprising a plurality of helically coiled wires of different twist with wires of right-hand twist alternating with wires of left-hand twist, cross rods extending the full width of the fabric and connecting the bights of pairs of the several helically coiled wires; said cross rods being crimped with the bends so spaced as to be engaged by the helices or coils of the respective cross wires, and reinforcing and strengthening means for the selvages of said fabric comprising a plurality of closely placed coils of the respective helically coiled wires disposed adjacent to the marginal edges of the fabric; each of said helically coiled wires being welded to an individual cross rod beyond said closely placed coils.

10 3. A wire fabric, composed of a plurality of helically coiled wires, cross rods extending the full width of the fabric and connecting the bights of pairs of the several helically coiled wires; said cross rods being crimped with the bends so spaced as to be engaged by the helices or coils of the respective cross wires, and reinforcing and strengthening means for the selvages of the fabric including a plurality of closely placed coils of the respective helically coiled wires disposed adjacent to the marginal edges of the fabric with single reversely placed coils adjacent to each group of closely placed coils; each of said helically coiled wires being welded to an individual cross rod beyond said closely placed coils.

15 4. A wire fabric comprising a plurality of helically coiled wires of different twist with wires of right-hand twist alternating with wires of left-hand twist, cross rods extending the full width of the fabric and connecting the bights of pairs of the several helically coiled wires; said cross rods being crimped with the bends so spaced as to be engaged by the helices or coils of the respective cross wires, and reinforcing and strengthening means for the selvages of the fabric including a plurality of closely placed coils of the respective helically coiled wires disposed adjacent to the marginal edges of the fabric with single reversely placed coils adjacent to each group of closely placed coils; each of said helically coiled wires being welded to an individual cross rod beyond said closely placed coils.

20 5. A wire fabric comprising helically coiled wires with alternate wires of different twist, and cross rods extending the full width of the fabric and connecting pairs of said helically coiled wires throughout the extent of the same; each of said helically coiled wires having a plurality of closely placed coils at or adjacent to the marginal edges of the fabric and being welded to an individual cross rod beyond said closely placed coils.

25 6. A wire fabric comprising helically coiled wires with alternate wires of different twist, crimped cross rods extending the full width of the fabric and connecting pairs of said helically coiled wires throughout the extent of the same, and reinforced marginal edges for said fabric comprising the plurality of closely placed coils of said helically coiled wires; said crimped cross rods having straight ends underlying said groups of closely placed coils, and welded connections at the ends of said helically coiled wires and said cross rods.

7. A wire fabric comprising helically coiled wires with alternate wires of different twist, crimped cross rods extending the full width of the fabric and connecting pairs of said helically coiled wires of different twist throughout the extent of the same; said helically coiled wires having groups of closely placed coils at the marginal edges of the fabric and at a point intermediate said edges longitudinally of the fabric, and permanent connections at the ends of said helically coiled wires and said cross rods.

8. A wire fabric comprising helically coiled wires with alternate wires of different twist, cross rods extending the full width of the fabric and connecting pairs of wires of different twist throughout the extent of the same, reinforced edges for said fabric comprising groups of closely placed coils of each of said helically twisted wires, and permanent connections between the ends of the respective helically twisted wires and the cross rods.

9. The method of reinforcing wire fabric composed of a plurality of helically coiled wires which comprises arranging a plurality of said wires in juxtaposed position with respect to each other; threading crimped cross rods in engagement with the bights of pairs of directly adjacent helically coiled wires; arranging a plurality of coils of each of the helically coiled wires in closely placed relation adjacent to the marginal edges of the fabric, and welding the ends of the crimped cross rods to the ends of individual helically coiled wires at the marginal edges of the fabric.

10. The method of reinforcing wire fabric composed of a plurality of helically coiled wires which comprises arranging a plurality of wires of right-hand twist in alternate and juxtaposed position with respect to the wires of left-hand twist; threading crimped cross rods in engagement with the bights of pairs of directly adjacent helically coiled wires; arranging a plurality of coils of each of the helically coiled wires in closely placed relation adjacent to the marginal edges of the fabric, and welding the ends of the crimped cross rods to the ends of individual helically coiled wires at the marginal edges of the fabric.

11. The method of reinforcing wire fabric composed of a plurality of helically coiled wires which comprises arranging said wires in juxtaposed position with respect to each other; threading crimped cross rods in engagement with the bights of pairs of directly adjacent helically coiled wires; arranging a plurality of coils of each of the heli-

cally coiled wires in closely placed relation adjacent to the marginal edges of the fabric, associating a single reversely placed coil of each of the helically coiled wires adjacent to said closely placed coils, and welding the ends of the crimped cross rods to the ends of individual helically coiled wires at the marginal edges of the fabric.

12. The method of reinforcing wire fabric composed of a plurality of helically coiled wires which comprises arranging wires of right-hand twist in alternate and juxtaposed position with respect to wires of left-hand twist; threading crimped cross rods in engagement with the bights of pairs of directly adjacent helically coiled wires; arranging a plurality of coils of each of the helically coiled wires in closely placed relation adjacent to the marginal edges of the fabric, associating a single reversely placed coil of each of the helically coiled wires adjacent to said closely placed coils, and welding the ends of the crimped cross rods to the ends of the individual helically coiled wires at the marginal edges of the fabric.

13. The method of reinforcing wire fabric composed of a plurality of helically coiled wires which comprises arranging a plurality of said wires in juxtaposed position with respect to each other; threading crimped cross rods in engagement with the bights of pairs of directly adjacent helically coiled wires; arranging a plurality of coils of each of the helically coiled wires in closely placed relation whereby a plurality of bights of each of the helically coiled wires independently engage a plurality of bends of the crimped cross rods, and welding the ends of the crimped cross rods to the ends of individual helically coiled wires at the marginal ends of the fabric.

14. The method of reinforcing wire fabric composed of a plurality of helically coiled wires which comprises arranging a plurality of wires of right-hand twist in alternate and juxtaposed position with respect to the wires of left-hand twist; threading crimped cross rods in engagement with the bights of pairs of directly adjacent helically coiled wires; arranging a plurality of coils of each of the helically coiled wires in closely placed relation whereby a plurality of bights of each of the helically coiled wires independently engage a plurality of bends of the crimped cross rods, and welding the ends of said rods to the ends of individual helically coiled wires at the marginal edges of the fabric.

OTTO CARL SCHERFEL.
